UNITED STATES PATENT OFFICE.

CARL A. BECHSTEIN AND EWALD E. KORNITZ, OF MILWAUKEE, WISCONSIN.

APPARATUS FOR DRYING LEATHER.

Application filed August 6, 1920. Serial No. 401,683.

To all whom it may concern:

Be it known that we, CARL A. BECHSTEIN and EWALD E. KORNITZ, citizens of the United States, and residents of Milwaukee, in the county of Milwaukee and State of Wisconsin, have invented new and useful Improvements in Apparatus for Drying Leather, of which the following is a description, reference being had to the accompanying drawings, which are a part of this specification.

This invention relates to certain new and useful improvements in apparatus for drying skins and leather.

It is the present custom, in drying skins or leather, to stretch the same upon a backing or board, and attach it thereto by nails or other fasteners. This method is unsatisfactory as the skin or leather is not evenly stretched, and, furthermore, consumes an unusual long time in the stretching thereof.

Hence, with the above and other objections in mind, this invention has for one of its objects to provide a frame upon which a skin or leather may be readily attached, and then evenly drawn taut to properly stretch the same.

Another object of this invention is to provide a frame for stretching leather, preferably of perforated material, whereby the skin may be easily attached thereto and the perforations provide ventilating means for thoroughly drying the skin.

A further object of this invention is to provide an expandable frame including a plurality of sections having means for simultaneously adjusting each section.

A still further object of this invention is to provide a leather drying frame which will be efficient in operation, and practical for the purposes described.

With the above and other objects in view which will appear as the description proceeds, our invention resides in the novel construction, combination and arrangement of parts, substantially as hereininafter described and more particularly defined by the appended claims, it being understood that such

changes in the precise embodiment of the herein disclosed invention may be made as come within the scope of the claims.

In the accompanying drawing, we have illustrated one complete example of the physical embodiment of our invention constructed according to the best mode we have so far devised for the practical application of the principles thereof, and in which:

Fig. 1 is a view looking at the top side of our improved expandable frame, a skin being shown in dotted lines as attached thereto, and parts being broken away to illustrate structural details;

Fig. 2 is a view similar to Fig. 1 of a slightly modified form of expandable frame;

Fig. 3 is an enlarged fragmental view of a portion of the screen illustrating one manner of securing a skin thereto;

Fig. 4 is a view similar to Fig. 3 illustrating our invention as in use in connection with a toggle, the toggle having parts broken away and in section; and

Fig. 5 is a top plan view of the toggle, illustrated in Fig. 4.

Referring now more particularly to the accompanying drawing in which like numerals designate like parts throughout the several views, the numeral 6 designates generally an expandable frame preferably formed of screen or any other material perforated as at 7, through which perforations the outer ends 8 of attaching hooks 9 are engaged.

In use, a length of leather or a skin 10 has the inner ends 11 of a plurality of the hook members 9 engaged therein along its edges as depicted in Fig. 3, when the skin is stretched as much as possible by the human hand, and the ends 8 of the hooks engaged in the adjacent apertures 7. When the skin has been thus placed upon the frame 6, the various sections thereof are expanded to draw the leather taut for drying, the apertures 7 across the back of the leather providing ventilating openings to assist in the thorough drying of the leather.

In that form of our invention depicted in

Fig. 1, the frame is formed in two sections, each section including a long frame portion 12 and a shorter frame portion 13, the portion 13 being readily slidably mounted between the upper extended ends 14 of the side bars or frame members 15 of the portion 12. One of the frame sections has the top and bottom frame members 16 thereof extended to provide means for slidably connecting the other frame sections thereto, and said frame members pass through bearing portions 17, formed on the extreme ends of the frame members 14 of said other section.

With this construction, the frame sections are permitted a movement toward and away from each other, and the portions 12 and 13 are permitted a movement toward and away from each other in a direction opposed to that of the frame sections. The frame sections and the frame portions are simultaneously moved in their various directions by jack-screw means now about to be described.

Having one end journalled as at 18 in the outer frame member 15 of one section of the frame 6, is a screw shaft 19 which extends across the back of the frame and has its other threaded end 20 engaged in a nut member 21 secured to the outermost frame member 15 of the other section. The shaft 17 has its journalled end provided with a handle or crank 22 whereby the same may be rotated to cause the sections to be moved toward and away from each other by reason of the threaded connection between the shafts 19 and the nut 21.

Each portion 13 is provided with a transverse brace 23 parallel with the shaft 19 and in which are journalled the lower ends of shafts 24 having their upper ends 25 threaded and engaged in nuts 26 carried by the upper ends of the portions 13. Secured to the lower ends of the shafts 24 are bevelled gears 27 meshing with bevelled gears 28 carried by the shaft 19, whereby the rotation of the shaft 19 to expand the frame sections will also expand the portions 13 as will be readily understood.

The gear 28 meshing with the gear 27 carried by the frame section mounted on the member 16, has a slidable but non-rotatable connection with the shaft 19 to permit the free adjustment of the frame section without breaking the connection between said gear.

In Fig. 2, we have illustrated a slightly modified construction of frame member formed in four complementary sections 29 having the side frame members 30 thereof slidably connected together. The corner bracket member 31 of each section has an inwardly extending internally threaded socket member 32 in which is engaged the outer threaded end 33 of a jack-shaft 34. The jack-shafts have their inner ends journalled as at 35 in bearings formed on a

spider member 36, and two of the axially aligned shafts 34 are formed in one.

Journalled in the spider 36 is an operating shaft, (not shown) which carries a main bevelled gear 37 for mesh with small bevelled gears 38 carried by a jack-shaft 34, the two shafts formed in one having but one gear 38. From this construction, it will be readily seen that when the gear 37 is rotated, the shafts 34 will be turned through the medium of their gears 38 to thus expand the sections and thus stretch the skin or leather 10 placed upon the screen.

In Figures 4 and 5, we have illustrated our invention in use in connection with a toggle, which consists of a frame provided with two upstanding bearing arms 40 having a journalled shaft or member 41 mounted therebetween which is operated by a handle 42 to bind the leather 10 between a projection 43 formed on the frame portion of the toggle proper, and a clamping member 44 pivotally carried thereby. Each toggle member has an apertured end 45 in which is engaged the end 46 of a hook 9 opposite its end 8.

What we claim as our invention is:

1. Apparatus of the class described comprising a plurality of sectional frames, means adapted to maintain said frames in a common plane and in a slidable relationship, means on said frames to which a hide or the like may be secured, and means adapted to effect a relative movement between said frames including a driving member and individual shafts operatively connected to said driving member and the respective frames.

2. An apparatus of the character described, comprising two parallel frames, means connecting the frames for transverse movement toward and away from each other and adapted to maintain the same in a common plane, an auxiliary section carried by each frame, means adapted to maintain each auxiliary section in a common plane with its adjacent frame and in a slidable relationship longitudinally toward and away from its frame, and means for effecting relative movement between the frames and auxiliary sections.

3. An apparatus of the character described, comprising two parallel frames, transverse guides extended laterally from the ends of one frame, means carried by the ends of the other frame and slidably engaging the guides to connect the frames in a common plane for transverse movement toward and away from each other, longitudinal guides carried by one end of each frame, an auxiliary section carried by each frame and slidable between the guides thereof, and means for effecting relative movement between the frames and auxiliary sections.

4. An apparatus of the character de-

scribed, comprising two parallel frames, transverse guides extended laterally from the ends of one frame, means carried by the ends of the other frame and slidably engaging the guides to connect the frames in a common plane for transverse movement toward and away from each other, longitudinal guides carried by one end of each frame, an auxiliary section carried by each frame

and slidable between the guides thereof, and 10 means for effecting simultaneous longitudinal movement of the auxiliary sections and transverse movement of the frames.

In testimony whereof, we affix our signatures.

CARL A. BECHSTEIN.
EWALD E. KORNITZ.
